DESIGN FOR A SCOOTER

Joseph M. Rodriguez, Brooklyn, N. Y.

Application December 4, 1939, Serial No. 88,683

Term of patent 14 years

To all whom it may concern:

Be it known that I, Joseph M. Rodriguez, a citizen of the United States, residing at Brooklyn, in the county of Kings and State of New York, have invented a new, original, and ornamental Design for a Scooter, of which the following is a specification, reference being had to the accompanying drawing, forming part thereof.

Fig. 1 is a side elevational view of a scooter, showing my new design;

Fig. 2 is a front elevational view thereof;

Fig. 3 is a top plan view;

Fig. 4 is an enlarged isometric detail view in perspective of the vertical arm, handles, and base portion shown in Figs. 1, 2, and 3;

Fig. 5 is an enlarged isometric sectional view in perspective taken transversely of the back part of the platform of the scooter; and

Fig. 6 is an enlarged transverse sectional view taken through the platform of the scooter.

I claim:

The ornamental design for a scooter, as shown.

JOSEPH M. RODRIGUEZ.
